ATTORNEYS.

UNITED STATES PATENT OFFICE.

STEPHEN G. WILSON, OF PHILADELPHIA, PENNSYLVANIA.

SHOE BRUSH.

Application filed October 14, 1921. Serial No. 507,593.

To all whom it may concern:

Be it known that I, STEPHEN G. WILSON, a citizen of the United States, residing in the city and county of Philadelphia, State 5 of Pennsylvania, have invented a new and useful Shoe Brush, of which the following is a specification.

My invention consists of a shoe brush formed of light metal or other suitable material having a perforated back and sides, outturned runways in said sides, slots and recesses in said runways, means for stiffening and strengthening said sides and back, and a frame or body carrier in said runways, 10 and means for locking said carrier and said body in said runways and back.

It consists also of a shoe brush having a body formed of fabrics of coarse and fine natures for different kinds of work, and a 20 frame or carrier attachable thereto adapted to carry said body in the back of the brush and permit said body to be reversed and so present either of its surfaces to the shoes.

It consists also of novel means for locking 25 said frame with the sides of the back. It consists also of other details as will be hereinafter set forth.

The invention is satisfactorily illustrated 30 in the accompanying drawings, but the important instrumentalities thereof may be varied, and so it is to be understood that the invention is not limited to the specific details shown and described, as long as they are within the spirit or scope of the claims.

Figures 1, 2, and 3 represent perspective 35 views of a brush embodying my invention, certain members thereof being in different positions in the different figures.

Figure 4 represents a longitudinal section 40 on line 4—4 Figure 3.

Figure 5 represents a transverse section on line 5—5 Figure 3.

Figure 6 represents a perspective view of the body of the brush in divided condition.

Figure 7 represents a perspective view of 45 the frame which carries the body within the back.

Figure 8 represents a perspective view of a bracing plate employed for the back or head 50 of the brush.

Figure 9 represents a perspective view of one of the stiffening members employed in the ends of the body.

Figure 10 represents a side elevation of 55 the device on a reduced scale.

Figure 11 represents a perspective view of

a member detached from its position shown in Figure 7.

Similar numerals of reference indicate corresponding parts in the figures. 60

Referring to the drawings.

1 designates the back or head of the brush, the same being formed of light metal or other suitable material comprising the top 2, and the depending sides 3 providing a chamber in said back. On the opposite inner faces of said sides 3 are the outturned parallel runways 4 and 5 which extend in the longitudinal direction of said back. 65

The runways 5 are formed by bending the lower ends of the sides 3 of the back or head of the brush into channel form thus acting as corrugations which stiffen and strengthen said ends. 70

6 designates a plate say of metal for bracing the back 1, the same having its sides adapted to be fitted in the runways 4. On a side of said plate are the resilient tongues 11 which are adapted to be sprung into the slot 12 in the adjacent portion of the runway 4, 80 thus locking the plate in the back.

On said plate 6 is the moistener 7 which is adapted to be fitted within the tongues 8 on the holder 9, which latter is adapted to be withdrawn through the open end 9^x of the 85 plate 6, as shown in Figure 8.

In order to retain said holder in position in the back, the handle 10 thereof is resilient and provided with a slot 10^x which is adapted to be sprung on the tongue or lip 90 10^x on the adjacent end of the back 1.

13 designates the rubbing material of the brush, the same being formed of a plurality of plies or pieces 14 and 15 of felt or other fibrous material of different natures, one of 95 them being a coarse fabric, and the other a fine fabric, said pieces being folded one within the other zigzag and exposing the coarse fabric on the upper side, and the fine fabric on the lower side of the body, so that 100 the coarse fabric may be used for removing dirt from the shoes, and the fine fabric may be used for the final finish of polishing.

In order to connect the body with the back 105 I provide the frame or carrier 16 which consists of the side bars 17, on one end of which is the handle plate 18 and the head 19. In the sides of said head 19 are slots 20^x in which the adjacent portions of the side bars 110 are received thus connecting said bars, plate and head. In the other plate 19^x are the

slots 22 which are adapted to receive the bifurcated lugs 21 which are adapted to be sprung into said slots 22 thus connecting said head 19^x with the adjacent ends of the arms 17. By these means also the frame is prevented from spreading and disconnection from the body.

The bars 17 are fitted in slits 29 formed in the sides of the body and they are adapted to be fitted in the runways 5, and so the body is connected with the back and carried thereon.

On the side ends of the plate 18 are the laterally projecting lugs or tongues 20 which are adapted to engage grooves or recesses 20^{xx} in the adjacent ends of the runways 5 and act as stops to limit the movement of the body into the back 1.

In order to hold the folds of the body firmly together cords 23 are passed through the grooves 29 in the body and recesses 25 in the end plates 24 and then properly tightened and tied, thus holding said body and plates in compact form.

Interposed between the end folds of the body 13 are the plates 24 which have in their sides recesses 25 through which the cords 23 and bars 17 pass, and between their sides the openings 26 into which contiguous portions of the sides of the adjacent folds of the body are compressed thus stiffening said portions and preventing lateral shifting of the plates.

On the sides of the bars 17 of the frame 16 are the ears 27 which project laterally therefrom and adapted to spring into the slots 30 in the sides of the runway 5, one of said ears having thereon the notch 28 which interlocks with the wall of the adjacent slot 30 and so prevents longitudinal shifting of the body in the back, and vice versa.

The frame 16 carrying the body of rubbing material 13 is applied to one end of the back and its ears 27 are fitting in the runways 5. The body is then slidingly pushed into the back to full extent being stopped by the tongues 20 abutting the recesses 20^{xx} in the end of the runways 5. Then the ears 27 spring into the slots 30, and the notch 28 engages with the wall of one of said slots and so the body is held in the back.

The brush may now be used first for removing the dirt from the shoes by the coarse material of the body. Then the body is drawn out partly from the back, the holding action of the notch 28 on the ear 27 being overcome. Then the body is overturned and the lugs 31 remaining in the runways 5, see Figure 2. Then the body is raised to full extent when the frame is introduced into the runways 5, at opposite ends of the sides and the body is pushed to full extent into the head, or back, the lugs 31 sliding in the runways 5 until the tongues

20 reach the recesses 20^{xx} and abut thereagainst thus stopping the motion of the frame and consequently that of the body of the brush, the ears 27 having sprung into the slots 29 and interlocking therewith.

The fine fabric of the head is now below and adapted to be rubbed on the shoe to complete the polishing.

The back is formed of light metal or other material which though strong is light in its nature, so the plate 6 is employed whereby said body and its sides 3 are stiffened and strengthened and so prevented from collapsing. The top 1 of the back is perforated to permit the moistener 7 to dry therein. When the body is worn, it may be removed from the carrier, and a new one substituted therefor and fitted in the carrier and back for rendering further service as hereinbefore described, while the back and carrier are retained therefor, and so to that extent the brush is renewable.

Having thus described my invention what I claim as new and desire to secure by Letters Patent, is:

1. In a polishing device, a backing member having a downwardly extending spring tongue at one end thereof, and downwardly extending parallel side walls extending the length of said back, said walls being provided with upper and lower channeled runways extending the length of said side walls, and slots in said runways intermediate their ends, the ends of the lower runways having grooves therein, and an adjustable drawer bracing plate in the upper runways of said side walls to brace said walls and backing member, and a moistening pad of fabric material mounted on a flat piece of metal having an upwardly extending resilient handle, said handle having a crosswise slot in its end, said pad and handle thereof being carried by the drawer bracing plate, the spring tongue in the end of said back set into said slot in said handle releasably holding said moistening pad in place, the top of said backing member having openings therein to facilitate the drying of said moistening pad when not in use, and a polishing pad carrying frame having means cooperating with the lower runways of said side walls.

2. In a polishing device of the character stated having a backing member, said back having a spring tongue at one end thereof, and downwardly extending parallel side walls extending the length of said back, said walls having upper and lower channeled runways extending the length of said walls, said runways having slots intermediate their ends, and an adjustable drawer bracing plate in the upper runways of said side walls, said bracing plate having one end and its two longitudinal sides rolled upwardly, said rolled up sides having two

spaced crosswise slots intermediate their ends, the middle section formed by the two crosswise slots in said rolled up sides being pressed outwardly forming a spring latch 5 for locking engagement with the slot in the upper runway of said side walls to adjustably hold said bracing plate in place, and a polishing pad carrying frame having means cooperating with said lower runways of said 10 side member.

3. In a polishing device, a backing member having downwardly extending parallel side walls, said walls being provided with upper and lower channeled runways extending 15 the length of said walls, and slots in said runways intermediate their ends, a drawer bracing plate carried by said upper runways, said plate to brace said back and side walls thereof, a polishing pad carrying frame having means cooperating with 20 said lower runways for detachably mounting said frame, notched lugs provided on said frame to engage the said slots in the lower runways to lock the frame in place, 25 one end of said frame being disengageable from said runways permitting the frame to be swung about its opposite end as a pivot for reversing the face of said polishing pad carried by said frame.

30 4. In a polishing device, a backing member having downwardly extending parallel side walls extending the length of said back, said walls being provided with upper and lower runways extending the length of said 35 side walls, and slots in said runways intermediate their ends, and grooves in the ends of the said lower runways, a drawer bracing plate in the said upper runways to brace the back and side members thereof, and a 40 carrier for a polishing pad removably engaged in said lower runways, means for

locking the carrier in position, said carrier comprising a frame formed of spaced resilient side members, plates connecting the corresponding ends of said side members, 45 said plates provided with slots adapted to receive slotted lugs provided on the corresponding ends of said side members of said frame for permitting releasable clamping of the pad within the frame, the opposite end 50 of said frame having on its sides outwardly extending lugs for abutting engagement in the aforesaid grooves in the ends of said lower runways to prevent said carrier from passing on through said runways and to 55 keep the end of said frame from knocking up and down when in use for polishing.

5. In a polishing device of the kind stated, a polishing pad comprising a laminated body formed of sinuously folded sheets of 60 fabric material, flexible cords reeved through said folds, the opposite side faces of said pad being slotted longitudinally midway of the polishing faces of the pad to receive said cord to bind the folds together, said 65 cord being tied at one end of said pad.

6. In a polishing device of the kind stated, a backing member having side walls, a carrier for a polishing pad detachably carried by said side walls, and a pad mounted in 70 said carrier, said pad comprising a sinuously folded sheet of flexible textile fabric, stiffening plates interposed between the folds of the pad, and flexible cords passing through the folds of said pad and the stiffening plates for retaining said folds and plates in shape. 75
